NECKTIE

Fred J. Urban, New York, N. Y., assignor to Hermann Spielmann & Son, Inc., a corporation of New York

Application February 27, 1957, Serial No. 45,012

Term of patent 3½ years

(Cl. D3—16)

Fig. 1 is a front perspective view of a necktie showing my new design as it appears in untied position; and

Fig. 2 is a cross-sectional view taken on line 2—2 of Fig. 1.

The dominant feature of the invention is a lace-like border stitched between the top front portion of the necktie and a central strip along the median portion of the front.

I claim:

The ornamental design for a necktie, substantially as shown and described.
